UNITED STATES PATENT OFFICE.

ARTHUR C. CIMAGLIA, OF MOUNT VERNON, NEW YORK.

WORKING-DRAWER FOR JEWELRY WORKERS.

1,270,496.

Specification of Letters Patent. Patented June 25, 1918.

Application filed August 8, 1917. Serial No. 185,216.

To all whom it may concern:

Be it known that I, ARTHUR C. CIMAGLIA, a citizen of the United States residing in the city of Mount Vernon, county of West-
5 chester, State of New York, have invented a new and Improved Working-Drawer for Jewelry Workers.

It is well known among makers of jewelry and other substances of precious metals, 10 that a considerable amount of metal filings and scrapings are lost by blowing away during the work and that it is very difficult to collect the metal dust.

The object of this invention is to provide 15 a receptacle for receiving and collecting the metal filings and to reduce the loss of same to a minimum.

I obtain this object by providing a drawer having its front face recessed and curved toward the interior with its central portion 20 raised somewhat above the three other sides, and the ends somewhat lower, being shaped thereby like an apron. The drawer is suitably supported below the work bench so 25 that it can be pulled out. The workman generally performs his work in a sitting position with the front end of the drawer supported upon his knees and the apron shaped front fitting around his body, while 30 his arms are supported on the depressed portion of the front and the two sides. The usual working pin is fixed at the front of 35 the work-bench in such a position that when the drawer is pulled out the pin is above the drawer. In this manner all metal filings and scrapings fall into the drawer and are thereby retained. Another important feature of my device is that the bottom and 40 three sides of the drawer are made of one piece of metal forming jointless edges and thereby making it very easy to collect the very fine metal dust which would collect at the joint between the sides and bottom of the drawer.

45 Other features and advantages will be apparent from the detailed description and the accompanying drawings forming a part of this specification and in which similar numerals refer to similar parts in all the 50 views and in which, Figure 1 is a perspective view of my device; Fig. 2 is a perspective view of my device showing a man in position at work; Fig. 3 is a plan view of the metal forming the drawer, before the 55 sides are turned upwardly; Fig. 4 is an elevation of the metal forming the front of the

drawer before it is bent to shape; Fig. 5 is a side elevation of the drawer; Fig. 6 is a front elevation of the drawer looking in the direction of line 6—6 Fig. 5 and Fig. 60 7 is a longitudinal sectional elevation of the drawer shown in perspective.

Referring to Fig. 3, the bottom 1 and the sides 2, 3 and 4 of the drawer are made of one sheet of metal by being bent up at the edges 5, 6 and 7. The bottom 1 has a semi-circular cut 8 into which the curved portion of the front side of the drawer is fitted. The drawer is supported on the runners 12 fixed beneath the bench 13 by means of the 65 vertical irons 12 and is prevented from being pulled off the runners 12 by means of the stop pieces 11. The working pin 14 is fixed at the front of the bench 13 so that it is over the center of the drawer. 70

The operation of the device is clearly shown in Fig. 2. The workman 15 is seated in front of the drawer with the bottom 1 resting upon his knees and the curved apron shaped front piece 9 fitting snugly around 75 his body, while his arms rest over the depressed portion of the front piece 10 and between the depressed portions 15 and 16 of the sides 2 and 3. It will now be evident that all metal filings and scrapings will fall 80 within the drawer and will be retained therein; after which it can be readily collected. 85

Having thus described my invention, I claim as new and wish to secure by Letters 90 Patent:

1. A device of the character described comprising a drawer having its front face curved toward the interior and the central portion of said face somewhat higher than 95 the sides for the purpose shown and described.

2. A device of the character described comprising a drawer having its front face curved toward the interior and the central 100 portion of said face somewhat higher than the sides and sloping downward toward the ends for the purpose shown and described.

3. A device of the character described comprising a drawer having its front face 105 curved toward the interior, the central portion of said face being somewhat higher than the ends and the two sides of the drawer being depressed somewhat near the front face for the purpose shown and described. 110

4. A device of the character described

comprising a drawer having its bottom and three sides made integrally, the front face of said drawer being curved toward the interior and its central portion somewhat higher than the sides for the purpose shown and described.

5. A device of the character described comprising a drawer having its bottom and three sides made integrally, the front face of said drawers being curved toward the interior, and its central portion somewhat higher than the ends, the two sides of the drawer being depressed somewhat near the front face for the purpose shown and described.

10. 6. A device of the character described comprising a working bench, a drawer slidably supported beneath said bench having

its front face curved toward the interior and its central portion somewhat higher 20 than the sides for the purpose shown and described.

7. A device of the character described comprising a working bench, a drawer slidably supported beneath said bench having 25 its front face curved toward the interior and its central portion somewhat higher than the sides for the purpose shown and described, and a working pin fixed at the front of said bench approximately over the 30 center line of said drawer.

Signed at the city of New York, county of New York and State of New York, this 7th day of August 1917.

ARTHUR C. CIMAGLIA.
